UNITED STATES PATENT OFFICE

HAROLD E. HALLENBECK, OF HUDSON, NEW YORK, ASSIGNOR TO GIFFORD-WOOD COMPANY, OF HUDSON, NEW YORK, A CORPORATION OF NEW YORK

TROLLEY BUCKET INSTALLATION

Application filed November 13, 1930. Serial No. 495,480.

This invention relates to improvements in trolley bucket installations, and among other objects, aims to provide means secured to the trolley to guide the bucket to the proper position relative to the trolley and prevent any relative movement of the bucket while the bucket is elevated to a position beneath the trolley, such means, however, interfering in no way with the bucket and permitting immediate lowering thereof. The invention provides means which may be used whatever the angular relationship of the monorail to the pit or pocket in which the bucket is loaded.

In the accompanying drawings of three embodiments of the invention,—

Fig. 1 is a vertical sectional elevation through a materials handling plant of the trolley bucket type, wherein the pit is at right angles to the vertical plane of the monorail, showing the trolley equipped with a structure which will prevent relative movement of the elevated bucket;

Fig. 2 is a side elevation on an enlarged scale showing the lower part of the trolley, also the bucket guiding and holding structure, the upper part of the bucket being shown in light lines;

Fig. 3 is an elevation at right angles to Fig. 2;

Fig. 4 is a side elevation of a bucket-guiding and holding structure which is designed for buckets which descend into pits or pockets extending parallel to the vertical plane of the monorail, the bail and upper part of the bucket being shown in light lines;

Fig. 5 is an end elevation of the parts of Fig. 4, the monorail being in section;

Fig. 6 is a top plan view of a small materials-handling plant, generally like the plant of Fig. 1, and on the same scale, but with the pit or pocket at an acute angle to the vertical plane of the monorail, the covers of the bins being omitted to show the bucket and its lines;

Fig. 7 is a top plan view showing in light lines the upper edge of the bucket, also the bail and sheave of the bucket, and in heavy lines the bucket-guiding and holding attachment which is used with the arrangement shown in Fig. 6; and

Fig. 8 is a side elevation from the right side of Fig. 7.

Referring particularly to Figs. 1 and 6, there is shown a small materials-handling plant comprising three storage bins or silos 55 10, a pit 11, a bucket 12, trolley 13, monorail 14, hoist line 15, traverse line 16, and counterweight line 17. Materials such as sand, gravel, coal, coke and the like are discharged, preferably by gravity from a railroad car 60 (not shown) on a siding 18, into a hopper 19, from the lower portion of which the materials flow when permitted by a swinging gate 20 under the control of the operator. The gate has an extension chute 21 for the materials to flow through, and chute 21 enters the upper part of the bucket, when the latter is lowered into the pit, so as to fill the bucket. When the bucket has its load, it is hoisted by hoist line 15, which leads to a hoist drum 22 70 driven by a motor 23. Spaced guides 24 located at the side of the pit co-operate with rollers 25 on the bucket to hold the bucket against tipping or twisting on its line, when hoisted. The bucket, when starting upwardly, closes the gate by its engagement with arms 26 on the chute 21.

When the bucket is hoisted to a point beneath the trolley, it is guided and held by a structure which is described hereinafter. 80 The trolley now moves in one direction or the other along the monorail 14, rollers 27 (Figs. 2 and 3) supporting the trolley and traveling over the lower flanges of the monorail. The trolley supports two vertical 85 sheaves 28, 29 (Fig. 2) by which the hoist line is supported, while the bucket has a sheave 30 on its bail 31 by which it is supported on the hoist line. Traverse of the trolley and bucket is effected by pulling in 90 one direction or the other on the traverse line 16, both ends of which are secured to trolley 13. Preferably there are two grooved traverse drums 32, 33 (Fig. 6) one of which is driven by a motor 34, and the traverse line 95 is wrapped about both drums so as to be reciprocated when the motor is driven in opposite directions, thereby to move the trolley and bucket back and forth under the monorail. When the bucket is over the bin 100

or pile where its load is to be deposited, the traverse line is held stationary, while the hoist drum pays out the hoist line, letting the bucket descend by gravity. The bucket has trip pads 35 (Fig. 1) which, when they come in contact with the top of the pile of material, trip the latches which hold the bottom of the bucket closed, allowing the bottom to open and the material to flow out by gravity. The bucket is then hoisted to contact with the trolley structure, the trolley is moved back to a position over the guides 24 leading to the pit and stopped, and the bucket is lowered to filling position adjacent the gate 20. Just before the bucket reaches the bottom of the pit, its bottom is closed by contact with an abutment 36, (Fig. 1).

It will be understood that while a pit is shown for receiving a load from a siding which is on the ground level, where an elevated siding is necessary, because of the contour of the site of the plant, a pocket wholly above the ground level (except for its foundations) will be employed.

The above brief description of a typical plant and the operation of the bucket which fills the silos will make clear the following fact: during each cycle of the bucket, it must be started twice and stopped twice in its traverse. Now the bucket is suspended from a flexible cable or rope by a sheave which rotates or travels over the hoist line during the traverse. Hence each time the trolley starts and stops, the bucket tends to swing, and unless prevented does swing, beneath the trolley. Theoretically this swinging is in the vertical plane of the monorail, as it is set up by the inertia and momentum of the bucket which moves beneath the monorail; but actually, the swinging is frequently lateral with respect to the monorail, as well as longitudinal, and often the bucket swings on the pivots of its bail as well as on the hoist line by which it is carried. This swinging is most undesirable, because it greatly slows up the operation of the bucket, as it is dangerous to lower the bucket while swinging.

In the pending W. H. Towne application, Serial No. 146,890, filed Nov. 8, 1926, assigned to the assignee of this application, a trolley bucket installation similar to the present one is described, wherein the trolley and bucket have buffers interposed between them to check swinging of the bucket beneath the trolley.

The buffers are very effective to check swinging of the bucket longitudinally, or in the vertical plane of the monorail, but are ineffective to check lateral swinging of the bucket. Indeed, so far as I am aware, no one heretofore has devised means interposed between the trolley and bucket to check and stop all swinging of the bucket and thus make the bucket move with the trolley as though rigidly secured thereto. The present invention provides such means, and also provides

means for guiding the bucket, as it rises to its uppermost position beneath the trolley, to assume the proper angular position relative to the trolley. The three embodiments of the invention to be described perform the functions stated, whether the bucket rises from a pit parallel to the monorail, or at right angles or at an acute angle.

Referring to Figs. 1, 2 and 3, the trolley 13 (the details of whose construction are more fully shown in Figs. 4 and 5) carries a spring buffer structure generally similar to the one described in the aforesaid Towne application and including four vertical coil springs 40, each mounted on a vertical rod 41 which is received within a spacing sleeve 42 passing through a cross bar 43, there being two of said cross bars 43 at the opposite ends of the trolley. At the lower end of each sleeve 42 is a foot piece 44 providing convenient means for attaching a horizontal cross member, preferably in the form of a channel 45. Two alined, spaced channels 46 are secured beneath channel 45 (Fig. 3) and project beyond the same. Secured to the outer ends of channels 46 are vertical channels 47, while diagonal braces 48 are secured at their lower ends to channels 47 and at their upper ends to cross bars 45, as well as to the channels 46 at the inner ends of said channels. The diagonals 48 thus converge upwardly, and being made preferably of angle iron, provide upwardly inclined flanges which serve as guides for the bail 31 of the bucket, as will be understood by referring to Figs. 1 and 3. The top of the bail 31 may strike either of the inclined surfaces provided by the inner flanges of the angles 48, and as there are two such angles at each end of the trolley, the bail is turned, causing the bucket to turn until the vertical plane of the bail is brought into the vertical plane of the trolley sheaves 28 and 29, in the embodiment of Figs. 1-3. The top of the bail 31 is then brought against the undersides of the spaced channels 45, as shown in Fig. 3. Extending between the vertical channels 47 are horizontal channels 49 and the union between these members is preferably strengthened by employing gussets 50 at the corners. Wooden strips 51 may be secured to the channels 49, fitting the space between the webs thereof, as clearly shown in Fig. 3. The wooden strips 51 provide replaceable contact members for contacting with the upper edges of the bucket 12.

The trolley construction shown in Figs. 1, 2 and 3 is especially designed for buckets which descend into pits or pockets at right angles to the vertical plane of the monorail, as shown in Fig. 1. In some instances, the pit is alined with the series of storage bins 10 and the bucket descends from one end of the monorail into the pit and rises again with its bail at right angles to the monorail instead of parallel thereto as in the arrangement of Figs. 130

2 and 3. It is obvious that the construction of Figs. 2 and 3 would not guide and hold a bucket whose bail is at right angles to the monorail. A trolley construction particularly adapted for what are known as "parallel" installations, that is, where the pit runs parallel with the monorail, is shown in Figs. 4 and 5. In these figures, the parts which are similar to those parts illustrated in Figs. 2 and 3 are designated by the same reference numerals, even though slight dimensional changes are necessary to make the structure depending from the trolley hold the bucket against any movement.

In Figs. 4 and 5, the converging diagonal members 48 are parallel to the monorail, so that the bail 31 is guided at right angles to the monorail and will pass up between the diagonal channels 48 and will be turned by said diagonals until the edges of the bucket are substantially in contact with the wooden strips 51. The vertical channels 47 are secured together by means of longitudinal horizontal members 52. Secured to the upper sides of the channels 52 are additional channels 53 (Fig. 4) which greatly strengthen the longitudinal members 52. The cross channels 45 extend across the tops of the longitudinal channels 52 substantially at the ends thereof and angle pieces 55 (Fig. 5) are secured to the uprights 47 and to the cross channels 45 and also to the longitudinal channels 52 to brace the structure at the four upper corners. The vertically movable members consisting of the sleeves 42 and rods 41 are secured to the channels 45 by foot pieces 44, which may be welded to insure rigidity.

In the two constructions shown in Figs. 2, 3, 4 and 5, the bail of the bucket, during hoisting, usually strikes one of the guiding members 48 and then the diagonally opposite guiding member and is quickly straightened until it occupies a vertical position either parallel with the monorail (Fig. 2) or at right angles thereto (Fig. 5). When the bail strikes the upper members 45 (Fig. 3) or 52 (Fig. 4), the entire structure which is secured to the members 45 or 52 is lifted against the resistance of springs 40, whose lower ends bear against washers 56 (Fig. 4) at the tops of the sleeves 42. The upper ends of the springs 40 about plates 57 which are rigidly fixed upon the trolley at each end thereof, as shown in Fig. 4, and which extend crosswise of the trolley as shown in Fig. 5. The springs 40 thus tend to hold the lower trolley structure in the position shown, but may be compressed when the sleeves 42 and rods 41 are moved upwardly through the plates 43 and 57. Thus the force of any blow delivered by the bail on the lower trolley structure is expended in contracting the four powerful springs 40, which absorb the shock and protect the trolley. Furthermore, the springs act individually at each of the four corners of the lower structure

to hold said structure substantially immovable, while yielding to heavy stresses.

As the vertical members 47 are of substantially the same length as the height of the bail 31, it follows that when the top of the bail is centered between the guides 48, two of the upper edges of the bucket are in contact or substantially in contact with the wooden strips 51; and as these wooden strips are always parallel to the vertical plane of the bail, which is pivoted as at 58 to swing about horizontal pivots, it follows that any tendency of the bucket to swing on the pivots of the bail is checked by contact of the upper edges of the bucket with the strips 51. This is true in the construction of Fig. 3, as well as in the construction of Fig. 4. Longitudinal swinging of the bucket, that is, swinging in the plane of the monorail, is impossible in the construction of Figs. 2 and 3 (except for a very brief interval) because of the contact of the upper edge of the bucket with the relatively long strips 51, and the great resistance offered by the springs 40 to overcome any thrust against said strips. Lateral swinging of the bucket for any length of time is impossible in the construction of Fig. 4, for the same reasons. As neither lateral nor longitudinal swinging is possible for any length of time in either construction, it follows that the bucket is substantially rigidly held against the underside of the lower trolley structure and is almost immovable, even when the trolley motor is started quickly and stopped suddenly. Any slight swinging which may be set up in any direction responsive to excessive stresses is very quickly checked by the four powerful springs, which act through the lower trolley structure to dampen and stop the swinging of the bucket.

In longitudinal swinging of the bucket, the two springs at one end of the trolley will act, followed by the two springs at the opposite end of the trolley, while in lateral swinging of the bucket, the two springs on one side of the trolley will act and then the two springs on the opposite side will function.

In Fig. 6 there is shown what is known as an "angle" installation, wherein the pit extends at an acute angle to the monorail. In this instance, it would be necessary to turn the bucket about a vertical axis to bring its bail either at right angles to or parallel with the vertical plane of the monorail. Such twisting and turning of the bucket would be very undesirable for several reasons, and in the illustrated construction the bucket is not turned at all but is hoisted from the guides without change in its angular position to a position adjacent the lower trolley structure and is then held against turning or swinging in any direction. To accomplish this result, the lower trolley structure is particularly constructed to receive the bail 31 and guide it

110

115

120

125

130

and hold it at an acute angle to the vertical plane of the monorail, as shown in Fig. 8.

Secured to the lower ends of the sleeves 42 are the two channels 45 to each of which are secured a pair of channels 60 and 61, said channels being spaced apart as shown in Fig. 8 to receive the bail 31 between their ends. There are vertical channels 47 at each of the four corners of the structure secured to the horizontal channels 60, 61. Diagonal channels 62 and 63 are at the opposite ends of the structure and are so placed as to guide the bail 31 into the proper angular position relative to the trolley. The angle which the bail 15 assumes relative to the monorail, as shown in Fig. 6, is the complement of the angle of the longitudinal axis of the pit relative to the monorail. Thus the bucket, when elevated and lowered from its guides, is not turned or 20 twisted about a vertical axis unless the hoist line has a tendency to turn the bucket, in which case the bail strikes two of the guides 62, 63 as the bucket is hoisted to its uppermost position. When the bail abuts the two 25 channels 45, the bucket is securely held against swinging on the bail pivots, also against swinging on the hoist line, and furthermore, cannot rotate about a vertical axis, due to the centering action of the two converging guides 62, 63.

The described constructions provide a bucket guiding and holding attachment for trolleys which is economically manufactured, which may be adapted to old installations, 33 and which substantially obviates relative movement between the bucket and trolley during traverse of the trolley, yet permits immediate lowering of the bucket at any time and place desired.

40 Obviously the present invention may be embodied in many forms not illustrated, and may be employed with buckets of various constructions, including buckets with bails made partly from chains or other flexible members 45 extending between some portion of the bucket and the cross-bar or other member which supports the sheave.

What I claim is:—

1. In combination, a trolley having two 50 spaced vertical sheaves; a bucket having a pivoted bail; a sheave mounted on the bail; a hoist line passing over the two sheaves on the trolley and under the sheave on the bail; a spring buffer structure mounted on and depending from the trolley; and a framework secured to and depending from the buffer structure, so that when struck by the bucket it will yield and compress the springs of said buffer structure; said framework being substantially in contact with the upper edges of the bucket and in contact with the bail when the bucket is hoisted to its uppermost position.

2. In combination, a trolley having two 65 spaced vertical sheaves; a bucket having a

pivoted bail; a sheave mounted on the bail; a hoist line passing over the two sheaves on the trolley and under the sheave on the bail; a spring buffer structure mounted on and depending from the trolley; and a framework secured to and depending from the buffer structure, so that when struck by the bucket it will yield and compress the springs of said buffer structure; said framework being substantially in contact with the upper edges of the bucket; said framework having upwardly converging guide members for directing the bail of the bucket toward the final position which it is to occupy when the bucket is hoisted to its uppermost limit.

3. In combination with a bucket having a bail; a hoist line for elevating the bucket by means of its bail; a trolley supporting the hoist line so as to permit traverse of the trolley and hoisting of the bucket independently; a shock-absorbing structure carried upon the trolley and engaged by the bail of the bucket when the latter is hoisted; means secured upon said shock-absorbing structure to guide the bucket by means of its bail, as the bucket is hoisted; and a framework also secured to said shock-absorbing structure to contact with the upper edge of the bucket, thereby to hold the bucket against swinging in any direction.

4. In combination with a bucket having a bail; a hoist line for elevating the bucket by means of its bail; a trolley supporting the hoist line so as to permit traverse of the trolley and hoisting of the bucket independently; and a framework secured upon the lower side of the trolley and having means contacting with the bail as the bucket nears its uppermost position for turning the bucket until it assumes the proper angular position relative to the trolley; said framework having members which are substantially in contact with the upper edge of the elevated bucket, thereby to hold the bucket against swinging in any direction.

5. In combination, a bucket; a hoist line for the bucket; a trolley supporting the hoist line; and a framework secured to and depending from the trolley and contacting with the upper edges of the bucket when the bucket is elevated to a point adjacent the trolley, providing a rigid abutment against which the bucket is held by the hoist line from swinging in any direction relative to the trolley.

6. In combination, a four-sided bucket having a bail pivotally attached to two opposite sides adjacent the top; a hoist line supporting the bucket by its bail; a trolley supporting the hoist line; and a framework secured to and depending from the trolley and adapted to contact with the bail at two spaced points at the top thereof and also adapted to contact with the upper edges of

the two sides of the bucket to which the bail is not attached.

7. In combination, a four-sided bucket having a bail pivotally attached to two opposite sides adjacent the top; a hoist line supporting the bucket by its bail; a trolley supporting the hoist line; a framework secured to and depending from the trolley and adapted to contact with the bail at two spaced points at the top thereof and also adapted to contact with the upper edges of the two sides of the bucket to which the bail is not attached; and a spring buffer at each end of the trolley, the springs of which are compressed by upward blows of the bucket or its bail against said framework.

8. In combination with a trolley for trolley bucket systems having a pair of vertical sheaves at its opposite ends; a spring buffer structure comprising two vertical coil springs carried at either end of the trolley on opposite sides of the sheave; a horizontal member connected to two vertical members at either end of the trolley, the two vertical members being adapted to compress the corresponding coil springs when moved upwardly by upward movement of the horizontal member; a pair of downwardly diverging guide members secured at their upper ends to each horizontal member; and a pair of bucket-engaging members each secured to two of the guide members and extending substantially horizontally and being so spaced as to be engaged by two opposite upper edges of the bucket when the bucket is hoisted close to the trolley, the guide members being adapted to straighten the bucket relative to the trolley by engagement with the bail of the bucket.

40 9. In combination with a trolley for trolley bucket systems having a pair of vertical sheaves at its opposite ends; a spring buffer structure comprising two vertical coil springs carried at either end of the trolley on opposite sides of the sheaves; a horizontal frame connected to two vertical sleeves which are at either end of the trolley, the two vertical sleeves being adapted to compress the corresponding coil springs when moved upwardly by upward movement of the horizontal frame; a pair of vertical members secured at their upper ends to the opposite ends of the frame and extending downwardly; a horizontal bucket-edge-engaging member secured to the lower ends of each pair of vertical members, said bucket-edge-engaging members being spaced apart the distance between the two opposite upper edges of the bucket to which the bucket bail is not attached; and a pair of spaced guiding members secured at the lower ends to each of the bucket-edge-engaging members and extending upwardly to the frame to which they are secured at a substantially central point; the two guiding members on either side of the trolley form-

ing a substantially inverted V-shaped guide for the bail of the bucket.

10. In combination with a trolley for trolley bucket systems having a pair of vertical sheaves at its opposite ends; a spring buffer structure comprising two vertical coil springs carried at either end of the trolley on opposite sides of the sheave; a horizontal frame connected to two vertical sleeves which are at either end of the trolley, the two vertical sleeves being adapted to compress the corresponding coil springs when moved upwardly by upward movement of the horizontal frame; a frame secured to and depending from the horizontal frame and comprising two guides for the bucket bail, each guide comprising two upwardly converging members of unequal length secured to the horizontal frame at their upper ends and spaced apart at said upper ends to admit the bucket bail; the lower ends of the guiding members being secured to a pair of horizontal members for engaging the upper edges of the bucket; the guides being so constructed and arranged that the bail of the bucket may extend at an acute angle to the vertical plane of the trolley and may be hoisted until its top engages said horizontal frame, being guided during such hoisting by contact near its opposite ends with said upwardly converging members.

In testimony that I claim the foregoing as my own, I have hereto affixed my signature.

HAROLD E. HALLENBECK.
